AUTOMATIC SUCTION RELIEF VALVE AND
AUDIBLE SIGNAL FOR TANK CAR SEGREGATORS

David Samiran, Osborn, Ohio

Application July 13, 1943, Serial No. 494,552

11 Claims. (Cl. 116—138)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to suction relief valves for fuel delivery conduits for relieving the suction within the conduit when the delivery of fuel is interrupted, or the suction or partial vacuum in the conduit exceeds a predetermined degree, and has for an object the provision of means for automatically venting the conduit to atmosphere when the suction therein reaches the aforesaid predetermined degree.

A further object is the provision of automatically operable venting means for liquid fuel delivery systems including a fuel delivery suction conduit, a fuel delivery pump for creating suction within the conduit to move the fuel therethrough, and a fuel segregator at the intake end of the conduit operable to automatically close the conduit to interrupt the flow of fuel therethrough upon the presence of a foreign liquid in the fuel being pumped having a different specific gravity from the fuel, in which the venting means includes signal means, operable to produce a signal when the venting means is in venting position.

A further object is the provision of automatically operable venting means for liquid delivery suction conduits, for venting the conduit to relieve the suction therein, in which the venting means is provided with audible signal means operable when the venting means is in venting position.

A still further object is the provision of suction operated venting means for fuel delivery suction conduits operable by the suction in the conduit when the same reaches a predetermined degree to admit a suction relieving fluid into the conduit to relieve the suction therein, and including fluid operated audible signal means associated with said venting means to be operated by the suction relieving fluid medium, incident to movement of said last named medium into said fluid delivery suction conduit.

A further object is the provision of suction pressure operated movable venting means for fuel delivery suction conduits having a suction relief port therein arranged to be uncovered when the venting means is in venting position to admit atmosphere into the suction conduit to relieve the suction therein, and a whistle means on the movable venting means operable by movement of the air passing therethrough into said suction conduit when the venting means is in venting position.

Other objects and advantages of the invention

will become apparent from the following description, taken in conjunction with the accompanying drawing, in which reference characters refer to like parts in the several figures.

Fig. 1 is a fragmentary side elevation of a portion of a fuel delivery system incorporating my improved combined suction relief means and audible signal therein, the fuel segregator and fuel delivery suction pump being shown diagrammatically.

Fig. 2 is an enlarged vertical sectional view through the suction relief means and audible signal structure, as disclosed in Fig. 1, showing the same in closed or inoperative position in full lines and in operative or venting position in dotted lines.

Referring to Fig. 1 of the drawing, the numeral 1 indicates a fluid delivery suction conduit having my improved venting means thereon, indicated generally at 2. The conduit 1 is preferably a rigid pipe having ribbed ends 1a and 1b to receive the flexible hose conduits leading respectively to the liquid fuel segregator A and the fuel delivery suction pump B. The segregator A is a conventional device which may be similar in construction to that shown in my patent No. 2,311,697 for closing the fuel intake end of the conduit 1 when a liquid of a different specific gravity from the fuel being pumped passes into the inlet. The pump B is of conventional construction, creating a suction pressure within the conduit 1 to cause the fuel to pass through the conduit and pump and be discharged through the fuel discharge conduit B' on the discharge, or outlet, side of the pump.

The conduit 1 is apertured at 3 to receive the flanged housing or cylindrical sleeve member 4, extending through the opening into the conduit 1 and terminating in an annular flat valve seat 5. The flanged portion 6 extending from this housing is secured to a saddle member 7, welded or otherwise secured to the conduit 1, and the means for securing the housing to the saddle member is indicated at 8. The interior of the sleeve member 4 is preferably cylindrical, and has spaced annular detent receiving grooves 9 and 10.

Slidably mounted within the sleeve member 4 is a cylindrical piston or valve member 11 having a head 12 at one end terminating in a sealing flange 13 adapted to seat on the valve seat 5 of the housing 4. The interior of this valve member 11 is open above the seat 5, as seen in Fig. 2, to provide a central venting passage 14 having a series of suction relief ports 15 extend-

ing through the wall, adapted to be uncovered to establish communication between the venting passage 14 and the interior of the fuel delivery suction conduit 1 when the valve is moved to venting position, as shown in dotted lines in Fig. 2 of the drawing.

An audible signal, or whistle device 16, is secured in the upper end of the venting passage 14 by suitable fastenings 17, this whistle device being formed of two thin concave sheet material members 16a and 16b, each having apertures 16c and 16d therethrough to produce an audible signal when air is drawn through the members to relieve the suction or partial vacuum within the fluid delivery conduit 1.

Manual means for moving the piston valve member 11 to its extreme positions is provided in the form of a handle member 18.

A spring loaded detent element is utilized to releasably retain the piston valve in either its non-venting or venting positions, said detent element comprising a tubular guide 19 extending across the center of the piston valve member 11 with its ends secured in openings in the annular wall thereof, said tubular guide having detent balls 20 and 21 therein at its opposite ends. Follower members 22 and 23 are disposed behind the balls with a compression coil spring 24 therebetween.

The spring 24 is preferably calibrated to retain the detent balls in the upper detent grooves 9 until a predetermined degree of suction exists within the fuel delivery conduit 1 so that the relative difference between the atmospheric pressure exterior of the conduit 1 and the partial vacuum within the conduit will cause the piston to be quickly moved inwardly to its operative or venting position seating the detent elements in the second detent groove 10.

In the operation of the device, the pump B creates a partial vacuum or suction within the conduit 1, causing fuel to be introduced through the segregator into the interior of the conduit, and drawn through the pump, and discharged at the point of delivery. In the event of water, or other foreign liquids of different specific gravity from the fuel being pumped, passing into the segregator A, this liquid segregator device will close the inlet end of the conduit, causing the pump to materially raise the degree of suction within the conduit. Since the suction pressure is operative on the piston head 12, this increased suction is sufficient to overcome the tension of the spring 24 holding the detents 20 and 21 in the grooves 9 of the flanged housing 4, the relief valve member will be immediately "snapped" inwardly to its venting position, as shown in dotted lines in Fig. 2 of the drawing, the ports 15, moving below the end of the flanged sleeve member 4, providing a substantially free venting passage through these ports between the atmosphere and the interior of the conduit 1.

Air passing through this passage must pass through the apertures 16c and 16d of the whistle member 16, causing an audible signal to be sounded, indicating that the pump is not delivering fuel, or indicating the presence of water or other liquid in the fuel being pumped.

When my venting device is used in connection with a suction conduit having a liquid fuel segregator, the reduction in suction occurring when the venting device is operating prevents any tendency for the suction to draw the foreign liquid, which closed the segregator, into the fuel conduit. While these segregators operate to shut

off the intake end of the fuel suction conduit when water is present in the fuel, such as gasoline, that is being pumped, there is sometimes a tendency for the segregator to fail to absolutely seal the intake end, and continued excess suction in the conduit might cause the foreign liquid to eventually be drawn up into the delivery conduit and discharged through the pump. By utilizing my improved automatic venting device, this problem is eliminated.

Having thus described my invention, what I claim and desire to secure by Letters Patent is:

1. In a fuel delivery system, including a fuel delivery suction conduit, pump means for creating suction in the conduit to draw a fluid therethrough, automatically operable suction relief means in communication with the interior of said suction conduit comprising a freely movable suction operated relief valve movable by the suction in the conduit to vent the conduit to relieve the suction therein, releasable interengaging detent means between the conduit and valve for yieldably supporting said relief valve in closed position, releasable by predetermined suction pressure within the conduit operable on the valve tending to move the same to allow the valve freely to move to its venting position under influence of the suction, and signal means associated with said relief valve operable upon movement of the valve to venting position to indicate that said valve is in suction relief position.

2. In a fuel delivery system including a fuel delivery suction conduit, pump means for creating suction within the conduit to cause movement of fuel therethrough and liquid segregator means at the fuel inlet end of the conduit to interrupt the flow of fuel thereinto upon the presence of an excess quantity of a foreign liquid of different specific gravity in the fuel being pumped, suction operated relief valve means in said conduit between said pump and said segregator, operable by a predetermined excess suction within the conduit due to said interruption of fuel flow to vent said conduit to relieve the suction therein when said suction exceeds a predetermined intensity.

3. In a fuel delivery suction conduit, venting means in the conduit to relieve the suction therein, comprising an annular casing opening into the conduit, hollow suction operated piston valve means having an annular wall slidably mounted in the casing to move axially thereof from non-venting position to venting position toward the interior of the conduit, said valve means having a suction relief port formed in the wall thereof in communication with atmosphere through the hollow portion constructed and arranged to be closed by said casing when the valve is in non-venting position, and uncovered to vent the suction conduit when the valve is moved inwardly to venting position.

4. In a fuel delivery suction conduit, venting means in the conduit to relieve the suction therein, said venting means comprising an annular casing opening into the conduit, suction operated hollow piston valve means slidably mounted within the casing to move axially thereof toward the interior of the conduit, said valve means having a suction relief port in its wall adjacent one end thereof, constructed and arranged to be closed by said casing when the valve is in closed position, and to be uncovered when the valve is moved inwardly in the casing toward the interior 75 of the conduit, and resiliently operable detent

means between the venting piston valve and said casing, releasably maintaining the piston valve in non-venting position, releasable upon application of predetermined suction pressure on the piston valve to permit the same to move to venting position.

5. In a fuel delivery suction conduit, venting means in the conduit to relieve the suction therein, said venting means comprising a casing opening into the conduit, suction operated valve means slidably mounted within the casing to move axially thereof toward the interior of the conduit, said valve means comprising a piston head having an annular wall forming a central venting passage leading to atmosphere, and a suction relief port extending through said wall adjacent the piston head thereof, constructed and arranged to be closed by said casing when the valve is in non-venting position, and uncovered when the valve is moved inwardly toward the interior of the conduit to venting position, releasable detent means between the piston valve and said casing for maintaining the piston valve in non-venting position, releasable upon application of predetermined suction pressure on the piston valve to permit the same to move under the influence of said suction pressure to venting position, and a whistle disposed in said valve in the venting passage, operable by air passing therethrough to relieve the suction in the conduit when the valve is in venting position.

6. In a pressure operated suction relief device for fuel delivery suction conduits, a tubular casing member fixed on the conduit having a central venting passage extending therethrough in communication with the interior of said conduit, said tubular casing having spaced detent receiving grooves formed in the inner wall thereof, and a cylindrical piston valve member longitudinally slidable in the central venting passage of the casing member, having a disc shaped piston head extending beyond the periphery thereof, to sealingly engage the end of the casing member in said fuel delivery suction conduit, and formed with an unobstructed central venting passage extending axially through said cylindrical piston valve member, said passage terminating in a plurality of radial vent openings, extending through the wall of the cylindrical piston valve member adjacent the disc shaped head thereof.

7. In a pressure operated relief device for fuel delivery suction conduits, a cylindrical casing member fixed on the conduit having a central venting passage extending therethrough into said conduit, said casing member having annular spaced detent receiving grooves formed in the inner wall thereof, a hollow cylindrical piston valve member slidably disposed in said cylindrical casing member, having a piston head extending across its inner end beyond the periphery of the central venting passage to sealingly engage the end of the casing member within the conduit and formed with an unobstructed central venting passage extending axially therethrough to said piston head, said passage terminating in a plurality of radial vent openings extending through the wall of the cylindrical piston valve member adjacent the piston shaped head, detent means on said piston valve member alternately engageable with said detent receiving grooves in the casing, and cooperating spring means for releasably holding said detent means in said detent receiving grooves.

8. In a pressure relief device for fuel delivery

suction conduits, a cylindrical casing member fixed on the conduit having a central longitudinal venting passage therethrough leading into said conduit, said casing member having spaced detent receiving grooves formed in the inner wall thereof, a cylindrical venting piston valve member slidably disposed in the central venting passage of said cylindrical venting piston member having a disc shaped head at its inner end, extending beyond the periphery thereof, to engage the inner end of the casing member adjacent the conduit and formed with a central venting passage extending axially through said cylindrical piston valve member to said disc shaped head and terminating adjacent said head in a plurality of radial vent openings extending through the wall of the cylindrical valve member, detent means alternately engageable with said detent receiving grooves, cooperating spring means for releasably

holding said detent means in said detent receiving grooves, and a suction operating audible alarm device carried in said central venting passage, operable by the air entering said relief passage to relieve the suction in said fluid delivery suction conduit.

10. In a suction relief device of the class described, a housing having an unobstructed cylindrical venting passage therethrough formed with a valve seat at one end, venting valve means slidably mounted to move in juxtaposed relation within the aforesaid cylindrical passage, having a central suction relief passage therein with a piston head at one end adapted to seat on the aforesaid valve seat and a plurality of suction relief ports extending through the wall of said valve adjacent the head, adapted to be uncovered when the valve head is moved off said seat, and suction operated whistle means positioned in the central suction relief passage of said valve between the end thereof and said suction relief ports.

11. In a suction relief device for suction operated fuel delivery conduits, a housing adapted to be secured to the fuel delivery suction conduit having an unobstructed cylindrical vent passage therethrough, formed with a valve seat at its inner end, and annular detent receiving grooves adjacent its outer end, a hollow cylindrical venting valve slidably disposed to move axially in juxtaposed relation to the aforesaid cylindrical passage, said venting valve having a flanged head adapted to seat upon the valve seat aforesaid when the valve is in closed position, and formed with lateral vent openings extending through the cylindrical wall thereof adjacent the flanged head, to be uncovered when the valve is moved to venting position to establish venting communication through the valve with the interior of the fuel delivery suction conduit, a whistle member disposed in the hollow central portion between the valve and the ports, a handle member extending across the end of the movable valve member for manual actuation thereof, and resiliently operable detent means between the casing and the slideable valve for releasably retaining the valve in its aforesaid positions.

12. In a suction relief device for suction operated fuel delivery conduits, a housing adapted to be secured to the fuel delivery suction conduit having an unobstructed venting passage therethrough, formed with a valve seat at its inner end, a hollow venting valve slidably disposed to move axially in juxtaposed relation to the aforesaid cylindrical passage, said venting valve

having a flanged head adapted to seat upon the valve seat aforesaid when the valve is in non-venting position, and formed with lateral vent openings extending through the wall thereof adjacent the flanged head, to be uncovered when the valve is moved to venting position, to establish venting communication through the valve with the interior of the fuel delivery conduit; a whistle member disposed in the hollow portion between the ports and the exterior of the valve; a handle member extending across the end of the movable valve member for manual actuation thereof, resiliently operable detent means between

the casing and the slidable valve for releasably retaining the same in its aforesaid positions, said detent means comprising annular detent engaging grooves formed in said flanged housing, tubular detent guide means extending diametrically through said venting valve, movable detent ball members disposed in the opposite ends of said tubular detent members for selectable engagement with said annular grooves in the casing, and spring means in said tubular detent passage for yieldably holding said balls in seating engagement with said annular grooves.

DAVID SAMIRAN.
